DESIGN FOR A FLUORESCENT LUMINAIRE

Frederic C. Winkler, Lakewood, and Carl F. Haas, Cleveland, Ohio, assignors to Westinghouse Electric & Manufacturing Company, a corporation of Pennsylvania

Application January 29, 1941, Serial No. 98,506

Term of patent 14 years

To all whom it may concern:

Be it known that we, Frederic C. Winkler and Carl F. Haas, citizens of the United States, and residents, respectively, of Lakewood, and of Cleveland, in the county of Cuyahoga and State of Ohio, have invented a new, original, and ornamental Design for a Fluorescent Luminaire, of which the following is a specification, reference being had to the accompanying drawing forming part thereof, in which:

Fig. 1 of the drawing is a perspective view, from below, of a fluorescent luminaire showing our new design.

Fig. 2 is a perspective view of the same as seen from above.

The side and end of the fluorescent luminaire not seen in the drawing have the same appearance as the side and end shown.

The dominant features of our design reside in the parts shown in solid lines.

We claim:

The ornamental design for a fluorescent luminaire, as shown and described.

FREDERIC C. WINKLER.
CARL F. HAAS.
